ENGINE STARTER GEARING

Maurice P. Whitney, Elmira, N. Y., assignor, by
mesne assignments, to Bendix Aviation Corporation,
South Bend, Ind., a corporation of Delaware

Application February 26, 1938, Serial No. 192,824

2 Claims. (Cl. 74—6)

The present invention relates to engine starter gearing and more particularly to manually operable devices for connecting a starting motor to a member of an engine to be started.

5 It is an object of the present invention to provide novel manually shiftable starter gearing which is positive and reliable in action while being simple and economical in construction.

It is another object to provide such a device 10 incorporating an overrunning clutch which is small and light but is arranged to carry heavy torque without undue localized stresses.

It is a further object to provide such a device 15 which is so constructed as to engage positively without jamming, and to overrun quietly and freely.

Further objects and advantages will be apparent from the following description taken in connection with the accompanying drawing in 20 which:

Fig. 1 is a side elevation partly in section of one preferred embodiment of the invention;

Fig. 2 is a section taken substantially on the line 2—2 of Fig. 1;

25 Fig. 3 is a view similar to Fig. 1 of a second embodiment of the invention;

Fig. 4 is a section taken substantially on the line 4—4 of Fig. 3;

Fig. 5 is a detail in side elevation partly in 30 section of structure similar to Fig. 1 with a rearrangement of the clutch controlling features; and

Fig. 6 is a section taken substantially on the line 6—6 of Fig. 5.

35 In Fig. 1 of the drawing, there is illustrated a power shaft 1 which may be the extended armature shaft of the starting motor, not shown, on which is journaled a driving member in the form of a pinion 2 with freedom for sliding movement 40 on the shaft 1 into and out of engagement with a member such as a flywheel gear, not illustrated, of an engine to be started.

Means for actuating the pinion 2 are provided including a hollow screw shaft 3 splined as indicated at 4 on the power shaft 1.

A driving clutch plate 5 is threaded on the hollow shaft 3 as indicated at 6, and a cooperating driven clutch plate 7 is non-rotatably connected to a barrel member 9 by means of driving lugs 8 engaging in slots 16 in the barrel. The barrel is rigidly fixed to the pinion 2 as indicated at 11. A stop nut 12 fixed on the end of the screw shaft 3 is arranged to form an abutment for the driven clutch plate 7, and longitudinal movement of the barrel with respect to the

driven clutch plate is prevented by means of a spacing sleeve 13 seated in the barrel against the clutch member, retained by suitable means such as a split lock ring 14 and prevented from rotation in the barrel by outturned flanges 15 engaging in one of the slots 16 in the barrel (Fig. 2).

Means for controlling the threaded clutch member 5 is provided in the form of a spring ring 17 bearing frictionally in a groove 18 in the 10 periphery of said clutch member and having an outturned end 19 engaging in one of the slots 16 of the barrel so as to anchor the ring to the barrel. The idle position of the clutch member 5 is preferably defined by a stop formed by the 15 abrupt termination of the thread 6. Such a stop is shown at 20 in Fig. 5.

Yielding means for sliding the pinion 2 and screw shaft 3 and their associated parts on the power shaft 1 so as to bring the pinion into and 20 out of operative position, are provided in the form of a shifting collar 21 slidably mounted on the smooth portion 22 of the screw shaft and maintained in engagement with a locking ring 23 on the screw shaft by means of a spring member 24 bearing against a shoulder 25 formed at the end of the threaded portion of said shaft. 25

In order to insure positive engagement of the clutch plates 5 and 7 without jamming action, the opposing faces of such clutch members are 30 provided with interengaging lugs and recesses 26 and 27 respectively.

In the operation of this embodiment of the invention, sliding movement is imparted to the shift collar 21 by any suitable shifting means 35 such as a manually operated fork engaging therein. When the pinion 2 has thus been caused to engage the flywheel gear of the engine to be started, the starting motor is energized in the usual manner, causing rotation of the power 40 shaft 1. This rotation is transmitted through the splines 4 to the screw shaft 3, and since the threaded clutch plate 5 is initially prevented from rotation by the frictional engagement of the spring ring 17 in the groove 18, said clutch plate 45 threads itself along the screw shaft until the clutch elements 26 thereof engage the clutch elements 27 of the driven clutch plate 7, whereupon the pinion 2 is positively connected for rotation with the power shaft 1. 50

When the engine starts, the acceleration of the pinion 2 causes it to overrun the power shaft 1, whereby the barrel 9 accelerates the threaded clutch member 5, first by the positive connection of the clutch elements 27, 26, and 55

thereafter by the frictional engagement of the spring ring 17 whereby the threaded clutch plate 5 is returned to its idle position on the screw shaft 3 as defined by the ends or heels 20 of threads 6, after which the pinion 2 and barrel 9 overrun freely as long as the pinion remains in mesh with the engine ring gear. When the manual shifting means is released, the parts are slid back to their idle positions on the power shaft 1.

In the embodiment of the invention illustrated in Figs. 3 and 4, a hollow shaft 28 is splined as indicated at 29 on a power shaft 31, and is fixed in any suitable manner as at 32 to a barrel member 33. A driving clutch plate 34 is non-rotatably mounted in the barrel 33 as by means of radial lugs 35 engaging in slots 36 in the barrel, and is retained in the barrel by means of a spacing ring 37 locked in the barrel by a split ring 38 and having outturned flanges 39 (Fig. 4) engaging in one of the slots 36 to prevent relative rotation between the ring and barrel.

A pinion 41 having a hollow threaded shaft 42 formed as an extension thereof or suitably fixed thereto, is slidably journaled on the power shaft 31, and a driven clutch plate 43 is threaded on the shaft 42 in position to cooperate with the driving clutch plate 34. The idle position of the clutch plate is preferably determined by abruptly terminating the threads of shaft 42 adjacent the pinion 41, or the pinion itself may form the stop for the clutch plate when the pinion and shaft 42 are formed separately, any suitable spacing means being interposed if deemed desirable. A stop nut 44 is fixed on the end of the shaft 42 to serve as an abutment for the driving clutch plate 34. Cooperating lugs and recesses 45 and 46 are provided on the opposing faces of the clutch elements 34 and 43 in order to establish a positive non-jamming driving connection therebetween.

Means for controlling the threaded clutch plate 43 is provided in the form of a spring ring 47 bearing frictionally in a groove 48 in the periphery of the clutch plate 43 and having an outturned end 49 engaging in one of the slots 36 of the barrel.

Means for sliding the pinion and splined shaft assembly on the power shaft 31 is provided in the form of a shifting collar 51 slidably mounted on the splined shaft 28 and yieldably held against a lock ring 52 seated in said splined shaft, by means of a spring 53.

In the operation of this embodiment of the invention, the pinion 41 is meshed with the engine ring gear, not illustrated, by any suitable shifting means such as a manually operated fork engaging the shift collar 51. Rotation of the power shaft 31 by the starting motor is thereupon transmitted through the splines 29 and shaft 28 to the barrel 33 which rotates the driving clutch plate 34 by reason of its positive anchorage therein, and rotates the driven clutch plate 43 through its frictional connection with the spring ring 47. Since the pinion 41 is at this time prevented from rotation by its engagement with the engine member, the driven clutch plate 43 is thus threaded into engagement with the driving clutch plate 34, whereupon the pinion 41 is positively connected to the barrel 33 for rotation therewith.

When the engine starts, the overrunning action of the pinion 41 with its screw shaft 42 causes the driven clutch plate 43 to thread itself away 75 from the driving clutch plate 34 to its idle posi-

tion as defined by the ends of the threads on shaft 42, or the end of pinion 41 as above set forth. The pinion, screw shaft and driven clutch plate thereupon overrun freely until the parts are returned to their idle positions by the shifting 5 means.

The embodiment of the invention illustrated in Figs. 5 and 6 is similar to that shown in Figs. 1 and 2 with the exception of the form of the controlling means for the threaded clutch plate, and the various elements of the structure are accordingly numbered as in Figs. 1 and 2. In this form of the invention, however, the spring ring 17a is anchored in the groove 19a in the threaded clutch plate 5 by means of its inturned end 19a, 15 and the ring bears frictionally on the interior of the spacing ring 13 as best seen in Fig. 6.

In the various embodiments of the invention illustrated, the spring friction ring which controls the threaded clutch plate is preferably arranged so that it is self-tightening in its action while causing the clutch members to engage. Thus in Fig. 2 of the drawing the rotation of the power shaft 1 is assumed to be in a clockwise direction whereby in the first embodiment of the 25 invention, the friction ring 17 contracts on the threaded clutch plate 5 as torque is transmitted therethrough. In Fig. 4 the friction ring 47 is similarly actuated by the counterclockwise rotation of the barrel 33 to frictionally grip the 30 threaded clutch plate 43. In Fig. 6 the friction ring 17a expands into gripping engagement with the interior of the spacing ring 13 in like manner responsive to counterclockwise rotation of the threaded clutch plate 5. 35

It will be readily appreciated that there is here provided a starter gearing which is positive in action without jamming and which overruns freely and quietly.

Although certain embodiments of the invention 40 have been shown and described in detail, it will be understood that other embodiments are possible and various changes may be made in the construction and arrangement of the parts without departing from the spirit of the invention as 45 defined in the claims appended hereto.

What is claimed is:

1. In an engine starter, a power shaft, a hollow shaft splined thereon, a pinion slidably journaled on the power shaft, and an overrunning clutch connection between the hollow shaft and pinion including a barrel member fixed to one of said members, a screw shaft fixed to the other, said barrel member having a plurality of longitudinal slots, a clutch plate in the barrel having 55 radial lugs traversing said slots, a clutch plate threaded on the screw shaft, said clutch plates having mating lugs and recesses, a sleeve anchored in the barrel in abutting relation to the first clutch plate, and a control member for 60 the threaded clutch plate in the form of an elastic split ring frictionally connecting the threaded clutch plate to the sleeve, said ring being anchored at one end to one of said members and being arranged to grip the other member with a self-tightening action when the power shaft is rotated to crank the engine. 65

2. In an engine starter, a power shaft, a hollow shaft splined thereon, a pinion slidably journaled on the power shaft, and an overrunning 70 clutch connection between the hollow shaft and pinion including a barrel member fixed to one of said members, a screw shaft fixed to the other, said barrel member having a plurality of longitudinal slots, a clutch plate in the barrel having 75

radial lugs traversing said slots, a clutch plate threaded on the screw shaft, said clutch plates having mating lugs and recesses, a split sleeve anchored in the barrel in abutting relation to the first clutch plate, having flanges engaging in a slot of the barrel to prevent rotation of the sleeve in the barrel, and a control member for the threaded clutch plate in the form of an

elastic split ring frictionally connecting the threaded clutch plate to the sleeve, said ring having an outturned end extending into said slot of the barrel and being seated in a groove in the periphery of the threaded clutch plate and arranged to grip said clutch plate when the power shaft is rotated to crank the engine.
